CAR HEATER VENTILATOR CONNECTION

Arthur B. Arnold, Racine, Wis., assignor to Modine Manufacturing Company, Racine, Wis., a corporation of Wisconsin

Application October 31, 1940, Serial No. 363,719

5 Claims. (Cl. 98—2)

The invention relates generally to heaters or the like, and more particularly to means for connecting a vehicle heater to a cowl ventilator or other similar opening.

In the last few years vehicle heaters have undergone numerous changes, one of which is the connection of the heater to an exterior source of fresh air, rather than merely heat and circulate the air inside the vehicle. In most instances the cowl ventilator of the vehicle is utilized for supplying fresh air to the heater.

However, due to the construction of both the vehicle and such new type of heaters, it was practically essential that they be designed for each other, in other words the heater was designed for the particular make or model and the vehicle designed to receive that particular heater. Consequently, such type of heater is employed substantially on only certain makes of cars and for which the heater was especially designed. Even in those makes of cars designed for such heaters difficulties were encountered due to slight inaccuracies in the assembly of the car body etc., which rendered it difficult to mount the heater in the car particularly in connecting the heater to the fresh air supply, the latter in most cases being the cowl ventilator. Obviously, where an all-metal heater construction is employed relatively slight inaccuracies in the car body hamper and slow up the installation of the heater.

The present invention has therefore among its objects the production of means for connecting a heater or other heat exchange device to a cowl ventilator, or the like, said connecting means being so constructed that inaccuracies in assembly are immaterial whereby the heater may be readily and efficiently installed in a minimum amount of time and effort.

Another object of the invention is the production of such a connector which is very simple in construction, inexpensive to manufacture, and very efficient and durable in use.

A further object of the invention is the production of connecting means which may be readily designed to fit various makes and models of automobiles so that by merely using the proper connector the same type of heater may be installed in cars of different makes and models, of both old and new cars.

A further object of the invention is the production of such a connector which will permit free movement of the ventilator cover, and at the same time provides a leak-proof water-tight connection from the cowl opening to the heater.

Many other objects and advantages of the invention herein shown and described will be obvious to those skilled in the art from the disclosure herein given.

To this end my invention consists in the novel

construction, arrangement and combination of parts herein shown and described and more particularly pointed out in the claims.

In the drawings, wherein like reference characters indicate like or corresponding parts:

Fig. 1 is a side elevational view of a heater and a portion of a cowl of a vehicle, the cowl and upper portion of the heater shown in section to illustrate the details of the invention;

Fig. 2 is a sectional view taken substantially on the line 2—2 of Fig. 1;

Fig. 3 is a sectional view taken approximately on the line 3—3 of Fig. 1;

Fig. 4 is a perspective view of the connecting means, the latter being shown partially in section; and

Fig. 5 is a sectional view illustrating the ventilator cover in an opened position.

Referring to the drawings and more particularly to Fig. 1, 1 designates generally an automobile heater, Fig. 1 showing the same in side elevation. The heater 1 may be of any suitable construction, that illustrated being of the so-called hot water type, having pipes 2 which may be connected into the cooling system of the car for operating the heat exchanger in the heater. The latter is designed for installation adjacent the bulkhead between the motor and passenger compartments, a portion of a bulkhead being shown in dotted lines as at 3.

The heater comprises a housing 4, having a fresh air inlet 5 at the upper end thereof, the inlet 5 being disposed, in the present instance, at an angle from the horizontal. The heater illustrated is provided with a filter 6 positioned intermediate the inlet 5 and the heat exchange unit (not shown) and in operation air is drawn through the inlet 5 and filter 6 from which it passes into the heat exchanger and out a suitable opening in the front side wall 7 of the housing into the passenger compartment. The specific details of the heater 1 including the filtering means 6 and heat exchanger form no part of the present invention, and therefore, are not shown in detail. The heater when installed, as illustrated in Fig. 1, is spaced from the underside of the cowl 8 of the vehicle body with the air inlet 5 of the heater disposed below and in approximate alignment with the cowl opening or ventilator, designated generally by the numeral 9. The latter is of the usual construction having a peripheral channel 11 in which is positioned a gasket 12 of rubber or other suitable material cooperable with the usual closure member 13 to seal the opening. The closure member 13, in the present instance, is pivotally supported from a suitable bracket 14 secured to a rigid part of the body, said pivotal support including a plate member 15 secured to and extending

downwardly from the bottom of the closure mem-

ber, arms 16 rigidly secured at each end to the plate 15 and each pivotally secured to the brackets 14 so that rotation of the arms 16 will raise the plate 15 and closure member 13 therewith to uncover the opening 9, as clearly illustrated in Fig. 5.

Connecting the opening 9 with the air inlet 5 is a flexible member 17 of a generally tubular shape. The latter at its upper end 18 is of approximately the same size and shape as the opening 9 and passes over the upwardly extending flange 19 forming the channel 11 where the free peripheral edges of the member are positioned below the gasket 12 and secured thereto by cement or other suitable means, thus, forming a substantially air and water-tight joint between the two. The member 17 may be formed of any suitable material preferably of a water-proof rubberized fabric, or the like, which would not permit the passage of water or air therethrough, at the same time being relatively flexible or pliable, and is cut and shaped by any of the usual methods. The opposite open end 21 is formed to fit the air inlet 5 of the heater unit with the walls of the member 17 positioned adjacent the periphery of the inlet. The member may be secured to the unit by any suitable means, one form being illustrated in the drawings, or by cement etc. In the present instance, the top 22 of the heater is provided with a downwardly extending flange 23 formed at the periphery of the inlet 5, the adjacent rear wall 24 of member 17 being folded back upon itself to enclose the flange 23. Overlying the portion of the member adjacent the inner face of the flange 23 is a bar 25, which, incidentally is provided with means 26 for holding the filter 6 in position. Rivets or bolts 27 pass through the bar 25, the adjacent folded portion of the member 17 and the flange 23 firmly securing the member to the housing 4. The side walls 28 and front wall 29 are similarly secured adjacent their bottom edges to the side walls 31 and front wall 32, respectively, of the housing 4, the extreme bottom edges of the walls 28 and 29 being folded back, as shown at 33, and positioned between bars 34 and 35, the bars 34 being positioned adjacent the side walls 31 and the bar 35 adjacent the front wall 32 of the housing. Bolts or rivets 36, similar to those used for securing the rear wall to the housing, pass through the respective bars and the adjacent folded over portion of the member 17 and side wall to secure the member 17 thereto. It will be noted that the fastening means 27 and 36 only extend through the folded over portion of the walls 24, 28, and 29 so that any water running down the inner walls of the member 17 will not come in contact with the fastening means, preventing rusting or corrosion of the same. The front wall 29 of the connecting member 17 is provided with slits 37 through which the closure supporting arms 16 extend, the front wall 29 being secured by cement or otherwise adjacent the slits 37 to the plate 15 to form an air-tight joint between the closure supporting means and the wall. A lug or ear 38 also secured to the plate 15 extends through a slit 39 in the wall 29, the slit being similarly sealed to prevent the passage of air or water therethrough. The ear 38, as illustrated in Fig. 1, may be connected with an operating handle 41 by any suitable means such as a link 42, so that the opening and closing of the closure member 13 may be controlled by the handle 41. Obviously, the arms 16 and ear 38 could if desired be mounted on a suitable bracket, positioned at the outer face of the wall 75

29 and fastened by bolts or other suitable means to the plate 15, instead of the construction illustrated.

It will be noted that the front wall 29 and the connecting member 17 is non-planar in shape, the length or height of the wall 29 being greater than the distance between the front wall 32 of the housing 4 and the corresponding edge of the opening 9. This fullness at the front wall permits that portion of the wall connected to the plate 15 and arms 16 to freely move up and down therewith, as the closure member is opened or closed. Thus, when the closure member is in a closed position, as shown in Fig. 1, the front wall 29 will have a bulged portion 43 positioned below the plate 15 while the upper portion 44 above the supporting member 16 is more or less flat. Similarly, when the closure member is in an open position, such as illustrated in Fig. 5, the lower portion 43 of the wall will be more or less flat while the upper portion 44 will be bulged. It will therefore be apparent, that the front wall 29 is of a length to permit that portion thereof, secured to the plate 15 to freely move with the closure assembly throughout the opening and closing movements thereof.

It will be noted from the above that the connecting member 17 provides means for effectively connecting the cowl opening 9 with the air inlet 5 of the heater unit, the member providing a substantially air and water-tight connection between the two, at the same time providing means whereby the easy action of the closure means is not affected, and at the same time providing an air and water-tight connection between the connecting member and the closed actuating means. Likewise, accurate alignment of the air inlet 5 with the opening 9, such as would be necessary, if a rigid connecting member were utilized, is eliminated as the flexible nature of applicant's connecting member readily compensates for inaccuracies in alignment whereby the use of applicant's device for installation of heaters in both old and new automobiles is clearly simplified. Any suitable insect screen may be provided either on the closure member 13 or positioned across the mouth of the opening 9.

When installed in new cars the heater unit may be installed in the usual manner without extremely accurate alignment of the air inlet with the cowl opening and after the unit is mounted on the bulkhead, the cowl gasket, carrying with it the adjacent portion of the connecting member 17, is passed through the opening and placed in its proper position, the same then being cemented down if desired. The supporting arms 16 of the closure means are then attached to the respective supporting brackets completing the installation. If the heater unit is to be installed in an old automobile a cowl gasket of the proper size having the connecting member 17 attached thereto is merely substituted for the original gasket on the car, the connecting member being cut or otherwise formed to provide passage of the closure supporting means through the side wall which is secured to said means in a manner similar to that previously described. Of course, in such installation it may be necessary to provide a slightly different form of actuating lever, etc., for that originally on the car. It will be apparent that the use of the present invention permits a dealer in auto heaters to carry substantially one type of heater, as such dealer can readily install the heater in various types of cars merely by using a connecting member and cowl gasket of

the proper shape and size. It would even be possible for the dealer to keep a stock of different sized cowl gaskets on hand, which the dealer could at the time of heater installation select the proper gasket and cement the connecting member 17 thereto. Thus, a single type heater could be installed in various cars, requiring the dealer to keep on hand merely different sized gaskets and at most several different types of connecting members. Obviously, by rendering a single type of heater substantially universal in installation, the dealer is not required to keep several different sizes and types in stock on hand with a consequent loss in profits.

It will be apparent from the above description that I have provided a novel connecting means for heaters, or other air conditioned units for vehicles, or the like, which provides efficient means for connecting the cowl opening with the air inlet of the unit, as well as, simplifying installation and rendering such unit substantially universal in application.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a connecting device of the kind described and in combination, a cowl having an air inlet therein, a cover therefor, a tubular shaped member constructed of pliable material having its upper edge secured to said cowl around the air inlet thereof and its lower edge secured to a stationary element around an air inlet, a plate secured to said cover and extending down into the interior of the tubular shaped member, and actuating means including a link disposed entirely exteriorly of the tubular shaped member, and connected to said plate by an ear which is secured to the plate and extends outward through a slit in a wall of the tubular member, and pivotally mounted arms secured to said plate and extending outward through slits in said wall of the tubular shaped member, said wall being adhesively secured to said plate around said slits, and said wall being of a size to allow bodily shifting movement of said wall together with said plate.

2. In an air conditioner for vehicles having a body, one wall of which has an opening therein for the passage of air therethrough, a heat exchange unit having an air inlet therein, a flexible member providing connecting means between said wall opening and the air inlet of said unit, a closure member for said opening, actuating means operatively related to said closure member for opening and closing the same, said means extending through and secured to one wall of said flexible member whereby the latter is bodily shifted by the movement of said actuating means to permit free operation of said closure member, said flexible member being tubular in shape and having one open end thereof connected to the periphery of said air inlet, a gasket member positioned adjacent the periphery of said wall opening engageable with said closure member to seal the latter, the opposite open end of said flexible

member being secured to said gasket to form a substantially air tight conduit extending from said wall opening to the air inlet of said heat exchange unit for the passage of air from said opening to said unit.

- 5 3. In an air conditioner for vehicles having a body, one wall of which has an opening therein for the passage of air therethrough, a heat exchange unit having an air inlet therein, a closure member for said opening, a gasket positioned adjacent the periphery of said opening cooperable with said closure member to seal the opening, a tubular flexible member having the peripheral edge of one open end thereof secured to said gasket, the peripheral edge of the opposite end being secured to said unit in registry with said air inlet, actuating means operatively related to said closure member for opening and closing the same, said means extending through one of the side walls of said flexible member intermediate the open ends thereof and secured to said one wall to form a substantially air tight juncture, said side wall being of a size to permit movement thereof with said actuating means when the latter is being operated to open or close said closure member.

- 10 4. In an air conditioner for vehicles having a body, one wall of which has an opening therein for the passage of air therethrough, a heat exchange unit having an air inlet therein, a closure member for said opening, a gasket positioned adjacent the periphery of said opening cooperable with said closure member to seal the opening, a hollow flexible member having the peripheral edge of one open end thereof secured to said gasket, the peripheral edge of the other open end being secured to said unit in registry with said inlet, actuating means operatively related to said closure member for opening and closing the same secured to a side wall of said flexible member, said side wall having a non-planar shape to provide a flexible wall having sufficient fullness to permit the same to move with said actuating means when opening and closing said closure member.

- 15 5. In an air conditioner for vehicles having a body, one wall of which has an air inlet opening therein, a heat exchange unit having an air inlet opening therein, a cover for controlling said air inlet opening in the wall of the body, a tubular connecting body constructed of pliable material, one end thereof being secured to said wall around said air inlet opening and the other end being secured to said heat exchange unit around the air inlet opening therein, a plate secured to said cover and extending down into the interior of the tubular connecting body, and actuating means for said cover including said plate and a link disposed entirely exteriorly of the tubular connecting body and connected to said plate by an ear secured to the plate and extending outward through a slit in one wall of said tubular connecting body, and swingable arms secured to said plate and extending outward through slits in said wall of the tubular connecting body, the latter and said plate being adhesively secured together around the slits, and said wall of the tubular connecting body being of a size to allow shifting movement of said wall when the actuating means is operated.
